THOMAS F. STRINGER, OF LORAIN, OHIO, ASSIGNOR TO THE THEW SHOVEL COMPANY, OF LORAIN, OHIO, A CORPORATION OF OHIO

POWER TRIP

Application filed February 15, 1929. Serial No. 340,146.

This invention relates to power trip means for a latch such as is employed in connection with the dump bottom of the dipper of a power shovel. The object of the invention is to provide power means for tripping the latch, which power means shall be operator controlled to trip the latch; and which when the latch is tripped, will automatically effect its own release from the applied power.

To this end I employ a driving member arranged for continuous rotation as by the governor-controlled power means by which the shovel is operated, a driven member having an eccentric portion associated with the latch to trip the same as the eccentric is thrown in one direction, means for yieldably urging the eccentric in latch-releasing direction, and overrunning clutch means between the driving and driven members. The overrunning clutch means to which reference is had is characterized by having portions positively interengageable when the driven member is being actuated by the driving member, but also characterized by ability to automatically disengage the drive upon overrunning of the driven member, that is, when the driven member moves ahead of the driving member. The arrangement is therefore such that after the eccentric completes its throw in latch-tripping direction and starts its return throw in latch-releasing direction, the yieldable means will cause the driven member to overrun the driving member and thus automatically release the tripping apparatus from its power drive. Therefore, operator-operated means being provided for effecting or initiating the drive, the operator need merely instantaneously actuate such means, and thereafter the dipper latch will be automatically tripped by power, and the power almost immediately disconnected. Further, however, should the apparatus fail to trip the latch in its first cycle of operation, continued or repeated functioning of the apparatus may be had by proper control of the operator-operated means until the latch is tripped; and in any event such repeated operation of the appa-

ratus can result in no damage to the parts.

The means yieldably urging the eccentric in latch-releasing direction may be resilient means incorporated as in the connection between the latch trip and the eccentric; or it may be a weight by which one of the driven parts is urged by gravity in an absolute direction; or it may be both of these means arranged to act together.

The exact nature of my invention together with further objects and advantages thereof will be apparent from the following description taken in connection with the accompanying drawings in which Fig. 1 is a more or less diagrammatic side elevation of a power shovel structure showing my invention incorporated as a part thereof; Fig. 2 is an enlarged detail of parts particularly pertaining to my invention and appearing in Fig. 1; Fig. 3 is a sectional detail of certain of the parts appearing in Fig. 2; and Fig. 4 is a sectional detail of parts indicated in Fig. 1, Figs. 2, 3, and 4 being views in the horizontal plane.

With reference now to the drawings, 1 is a carriage of the endless tread type indicated, 2 is a turntable mounted thereon, 3 is a boom, 4 a dipper stick, and 5 a dipper. It will be understood that movements of the boom are controlled through the rigging indicated, by power means on the table 2, not shown, but which may be the usual continuously-running governor-controlled internal combustion engine, acting through suitable drums and clutches for the purpose.

The dipper 5 is provided with a dump bottom 6 having a latch 7 by which the bottom 6 may be secured in closed position or released to dump the load.

What has thus far been described is old and well known in the art.

The trip means which comprises my invention takes its power from one of the continuously rotating parts on the table 2 such as the shaft 8 having bearing in the frame portion 9 of the machine.

The shaft 8 carries a driving member 10 slidable but nonrotatable thereon as by the keys 11. The member 10 has a groove 12 engaged by opposed finger portions 13 of

yoke 14. The yoke 14 is in turn carried by a lever 15 having fulcrum connection with the frame as at 16 on the fixed bracket 17, and an arm 18 with a handle portion 19. The rod 20 carries a spring 21 under its head 22 and passes through the lever 15. The arrangement is such that the member 10 is yieldably urged by the spring 21 inward of the shaft 8 and against the flange 23 fixed with the shaft; but whereby clockwise movement of the lever 15, Fig. 2, will slide the member 10 outwards of the shaft 8 and away from the flange 23.

On the extremity of the shaft 8 is a driven member 24 freely rotatable thereon as by bushing 25 and held in position by cap 26. The members 10 and 24 are provided with cooperating clutch teeth 27 and 28. The shaft 8 rotating in counterclockwise direction Fig. 1, the forward faces 27^a of its clutch teeth 27 lie generally in the central plane of the shaft and are preferably slightly undercut, but the rearward faces 27^b slope away as indicated. The forward and rearward faces of the teeth 28 are correspondingly arranged.

The member 10 thus provides means whereby the member 24 may be optionally driven by the shaft 8. This is accomplished by operator-operated effort upon the handle 19 to slide the member 10 to engage its teeth 27 with the teeth 28 of the member 20. Such driving engagement, where the member 20 is driven by the shaft 8, is positive and self-maintaining owing to the described arrangement of the forward faces of the teeth 27 and the corresponding rearward faces of the teeth 28.

It will be apparent, however, that should the member 24 overrun the member 10, that is, should it rotate in the same direction but at a higher speed than the member 10, the rearward faces of the teeth 27 will cooperate with the forward faces of the teeth 28 and act as cams to shift the member 10 upwards Fig. 2 and clear the two sets of teeth from each other, thus releasing the drive from the member 24.

The member 24 has an eccentric portion 29 which has connection with the latch 7. This connection is by way of the latchline 30. The boom 3 carries a shaft 31 upon which is a freely rotatable sheave 32 and a drum 33. The line 30 passes from the trip 7 over the sheave 32, over a sheave 34 mounted on the eccentric 29 and returns to the drum 33. The drum is yieldably urged as by a spring 35 in a direction to take up slack in the line 30 or pay out on the line so that bucket movements may be accommodated without effect upon the latch. The strength of the spring 35 and the relation of the parts is such, however, that a quick jerk upon the line 30, as by moving the eccentrically mounted sheave 34 about the

shaft 8 as a center, will effect tripping of the latch. Also the arrangement of the parts and particularly the spring 35 tends to maintain the eccentric in a position wherein the pulley 34 is nearest the drum 33.

While the drum 33 is illustrated and has been described as urged in latch-line winding position, the spring 35 is not essential provided the pitch diameter of the drum be that of the pinion which cooperates with the rack 4' of the dipper stick 4. If the drum and this pinion do have the same pitch diameter the drum 33 may be keyed to the shaft 31 to which the pinion is also keyed, and it will be apparent that the line 30 will be paid out or drawn in according to the movements of the dipper 5, all without interfering with the bight of the line 30 which passes over the sheave 34. Thus the sheave 34 is equally operable to trip the latch as before.

Thus when the member 24 is driven by the shaft 8 the eccentric will be thrown to give the desired latch-tripping jerk to the line 30. Also, after the eccentric passes its center with respect to the drum 33, and is on its return or latch-releasing stroke, the action of the spring 35 will act to move the member 24 in the direction in which it is driven by the shaft 8. Thus the member 24 will be caused to overrun the member 10 and by virtue of the clutch teeth described automatically throw off the drive.

In order to assist the spring 35 I may provide additional means for balancing the member 24 to provide an additional tendency of the same to overrun its driving member through the desired portion of its cycle of movement. This means comprises a counter-weight 36 which as shown is simply an additional enlarged arm on the member 24 and so arranged with relation to the eccentricity of the arm 29 that the center of gravity of the member 24 naturally tends to maintain it in the same absolute position in which the spring 35 and cooperating parts tend to maintain it. Thus during the return stroke of the eccentric, when the spring 35 is tending to cause the driven member 24 to overrun its driving member, so also does the weight of the member 36 tend.

Thus ordinarily merely momentary actuation of the handle 19 effects engagement of the clutch and consequent tripping of the latch, disengagement of the clutch being automatically effected by the means described. However, should the latch not be tripped in the first cycle of operation of the member 24, or should the operator continue depression of the handle 19, the cycle is simply repeated until the latch is released or until the handle 19 is released.

What I claim is:

1. Apparatus for tripping a dipper latch and comprising a rotating driving member, a driven member having an eccentric

portion associated with said latch to trip the same as said eccentric is thrown in one direction, means arranged to yieldably urge said eccentric in latch-releasing direction 5 during its return throw, driving connection for said members having interengageable portions characterized by ability to automatically disengage upon overrunning of the driven member, and operator-controlled means for effecting said drive.

2. Apparatus for tripping a dipper latch and comprising a rotating driving member, a driven member having an eccentric portion associated with said latch to trip the same as said eccentric is thrown in one direction, said association including counter-weight means whereby said eccentric is yieldably urged in its driven direction during its return throw, driving connection 15 for said members having interengageable portions characterized by ability to automatically disengage upon overrunning of the driven member, and operator-controlled means for effecting said drive.

3. Apparatus for tripping a dipper latch and comprising a rotating driving member, a driven member having an eccentric portion associated with said latch to trip the same as said eccentric is thrown in one direction, counter-weight means tending to balance said eccentric in latch-released position, means arranged to yieldably urge said eccentric in latch-releasing direction during its return throw, driving connection 30 for said members having interengageable portions characterized by ability to automatically disengage upon overrunning of the driven member, and operator-controlled means for effecting said drive.

4. In a machine of the class described and having a frame, a dipper and operating means therefor, said dipper having a door and a latch for said door, means for tripping said latch and comprising a rotating power operator, an operating member having an eccentric portion, connecting means associating said eccentric portion with said latch and adapted to be given back-and-forth movement by said eccentric and to trip the latch during movement in one direction, operator-controlled means for producing operative association of said power operator with said operating member for actuating the latter to trip the latch 55 and characterized by ability to automatically disengage upon overrunning of said operating member, and energy-returning means associated with said operating member for causing the same to overrun said operator after said latch has been tripped.

5. In a machine of the class described and having a frame, a dipper and operating means therefor, said dipper having a door and a latch for said door, an operating member connected to said latch for trip-

ping the same and movable through a cycle of operations for the purpose, a power operator therefor, means for producing operative association of said operator with said operating member for actuating the latter to trip the latch, and energy-returning means associated with said operating member to receive energy therefrom during a part of said cycle, and to give up said energy during a later part of said cycle to automatically release said association.

6. In a machine of the class described and having a frame, a dipper and operating means therefor, said dipper having a door and a latch for said door, an operating member arranged to have back-and-forth movement and connected to said latch for tripping the same by a part of said movement, a power operator therefor, means for producing drive of said operating member by said operator for actuating the former to trip the latch, and energy-returning means connected with said operating member and arranged to become effective by another part of said movement to release said association.

7. In a machine of the class described and having a frame, a dipper and operating means therefor, said dipper having a door and a latch for said door, means for tripping said latch and comprising a rotating power operator, an operating member having an eccentric portion, connecting means associating said eccentric portion with said latch and adapted to be given back-and-forth movement by said eccentric and to trip the latch during movement in one direction, operator-controlled means for producing operative association of said power operator with said operating member for actuating the latter to trip the latch, and energy-returning means connected with said operating member and arranged to become effective to automatically release said association as said connecting means moves in the other direction.

In testimony whereof I hereby affix my signature.
